UNITED STATES PATENT OFFICE

2,358,878

SEWING MACHINE

Joseph H. Pikul, West Newton, Mass.

Application July 11, 1941, Serial No. 401,932

2 Claims. (Cl. 112—252)

This invention relates to sewing machines, and especially, although not exclusively, to button hole sewing machines of the type known as "straight hole" machines, described, for example, in Patents Nos. 714,284, November 25, 1902; 749,776, January 19, 1904; 1,088,652, February 24, 1914; 1,402,073, January 3, 1922, and 1,483,307, February 12, 1924.

The invention relates particularly to thread cutting or trimming mechanisms for machines of this and other types, and has for one object to provide simple means, operable upon the completion of the stitching operation, first to set the final stitch, and then to cut or trim the thread.

Button hole sewing machines of the "straight hole" and some other types include a cutter for cutting the button hole slit substantially upon the completion of the stitching operation and another cutter operable immediately thereafter to sever or trim the sewing thread. In some such machines, the button hole cutter is timed to operate just prior to the completion of the sewing cycle, usually during the formation of the last stitch, and the thread cutter or trimmer to operate immediately upon the completion of the last stitch and the stopping of the machine. In many such machines the button hole cutter and the thread trimming cutter are obliged to operate in intersecting or closely adjacent paths. Normally, the button hole cutter completes its operation and is retracted or raised just prior to the operation of the thread cutter, but should the button hole cutter be inadvertently jammed in the work and fail to rise promptly, there is a possibility of its being struck by the thread cutter with resulting damage to one or both cutters. The present invention has for another object to provide button hole and thread cutting mechanism of such character that operation of the thread cutter is rendered automatically contingent upon the retraction of the button hole cutter.

The foregoing and other objects of the invention, together with means whereby the latter may be carried into effect, will best be understood from the following description of a preferred embodiment thereof shown in the accompanying drawings, this, however, having been chosen for purposes of exemplification merely, since the invention, as defined by the claims hereunto appended, may be otherwise embodied without departure from the spirit and scope thereof.

In said drawings:

Fig. 1 is a side elevation, partly broken away, of a machine embodying the invention, certain parts whose particular construction and arrange-

ment are not essential to the understanding of the present invention, and which may be substantially as more fully shown and described in the patents above referred to, being omitted for the sake of simplicity of illustration.

Fig. 2 is a plan view of the machine as shown in Fig. 1.

Fig. 3 is an end elevation, partly broken away, as viewed from the left in Figs. 1 and 2.

Fig. 4 is an end elevation as viewed from the right in Figs. 1 and 2.

Fig. 5 is a fragmentary view of certain parts shown in Fig. 4, showing said parts in a different position.

Figs. 6 and 7 are diagrammatic perspective views illustrating the operation of the combined stitch setter and thread trimmer.

The machine shown in the drawings, which, as above stated, may, as to its general organization, be similar to those described in the patents above referred to, comprises a bed 15 from which rises a standard 16 carrying an overhanging arm 17 spaced above the bed. The work W is carried by a work clamp or holder comprising a clamp plate 18 and cooperating clamping arms 19, said work holder being movable as a unit over the bed, by mechanism not shown, in order to position the stitches along the sides of the button hole. The stitch-forming instrumentalities comprise an eye-pointed needle 20 above the work and cooperating loopers or equivalent under thread handling devices 21 below the work, there being a throat plate 22 carried by the bed 15 and having an opening through which the needle operates. The needle 20 is carried by a needle bar 23 which is longitudinally and vertically reciprocated, by means generally indicated at 24, in a needle bar guide 25, means, not shown, being provided for oscillating said needle bar guide alternately in opposite directions transversely to the direction of feed of the work clamp between successive strokes of the needle to position the depth stitches. The thread t from a suitable source passes, through a take-up 26 and suitable tension devices 27 and 28, to the needle eye, whence it passes through the work and throat plate to the loopers 21. A main shaft 29 journaled in suitable bearings in the bed has power applied thereto by a belt 30 alternatively engageable with fast and loose pulleys 31 and 32 under the control of a belt shifter 33. The belt shifter 33 constitutes an extension of a stop member or arm 34 carried by an oscillating and longitudinally movable rock shaft 35 mounted for oscillation and a limited longitudinal movement in the bed 15. Slidably mounted in the

45 50 55 60 65 70 75 80 85 90 95

stop arm 34 is a stop element or bolt 41 normally urged toward the right in Figs. 4 and 5 by a spring 42. At its end the bolt 41 is formed with a nose 43 which, when the shaft 35 is in the longitudinal position to cause the belt shifter 33 to engage the belt 30 with the loose pulley 32, is in the path of movement of a cam 44 fast on the shaft 29, said cam having a concentric portion *a*, a rise *b*, a notch *c* and a stop shoulder *d*, arranged to engage the nose 43 in the order named when the shaft is rotated in the direction of the arrow in Figs. 4 and 5. The nose 43, when in the path of movement of the cam 44, is held in engagement with the periphery of the latter by a spring-pressed plunger 45 carried by the upright 16 and engaging the stop arm 34, said plunger tending to turn said arm and the rock shaft 35 in a clockwise direction, as shown in Figs. 4 and 5, and thereby press the nose 43 against the periphery of the cam 44.

The button hole cutter 50 is carried by a lever 51 journaled on a short stud shaft 52 supported in the bed, said lever having an arm 53 carrying at its end a sleeve 54 in which is journaled a stud 55 having at one end a sleeve portion 56 which receives a stud 57 extending inwardly from the stop arm 34.

The construction, arrangement and mode of operation of the parts above referred to, and certain associated parts, are, or may be, substantially as more fully described in the above mentioned patents. Associated with the sliding rock shaft 35 is a spring 65 (Fig. 2) surrounding said shaft and interposed between a collar 66 thereof and one of the bearing brackets or ears 67 in which said shaft is mounted, said spring tending normally to move said shaft toward the right in Fig. 2 into the position shown in the drawings, in which the belt 30 is engaged with the loose pulley 32 and the nose 43 of the stop bolt 41 is in the path of movement of the cam 44. To start the machine, a starting lever 68 is operated to move the shaft 35 toward the left in Fig. 2, thereby shifting the belt 30 from the loose pulley 32 to the fast pulley 31 and moving the nose 43 out of the path of movement of the cam 44, said shaft 35 being retained in this position by engagement of a detent 69 with a recess 70 therein. The detent 69 is controlled by mechanism (not shown) associated with the feeding means for the work clamp and adjustable in accordance with the length of the button hole to be sewn, the arrangement being such that just before the conclusion of the sewing cycle, and at about the beginning of the last stitch-forming cycle, the detent 69 is withdrawn from the notch 70, whereupon the spring 65 causes the shaft 35 to be restored to its normal position, thereby shifting the belt 30 from the fast pulley 31 to the loose pulley 32 and bringing the nose 43 into the path of movement of the cam 44. During the formation of the last stitch, the machine runs under its own momentum and the nose 43 follows the periphery of the cam 44. As said nose is engaged by the rise *b* of said cam, the stop arm 34 is lifted against the action of the spring-pressed plunger 45 into the position shown in Fig. 5. This lifting of the stop arm 34 operates, through the stud 57 and its connection with the arm 53 of the lever 51, to advance or depress the button hole cutter 50 and cause the same to cut the button hole slit. Thereafter the nose 43 drops off of the rise *b* of the cam 44 and, under the influence of the spring-pressed plunger 45, enters the notch *c*, as shown in Fig. 4, this movement causing the button hole cutter 50 to be re-

tracted or raised to its original normal position. The nose 43 is thereupon immediately engaged by the stop shoulder *d*, thereby positively stopping the machine at the completion of the final stitch, the stopping impact being cushioned by a yielding of the bolt 41 toward the left in Fig. 4 against the tension of the spring 42.

In accordance with the present invention, a combined stitch-setting and thread-trimming element 75 is guided in ways in the bed 15 immediately below the throat plate 22 and between the latter and the loopers 21. At the completion of the last stitch-forming cycle, and substantially coincidentally with the stopping of the machine, said element is moved, by means hereinafter described, from its normal retracted position, shown in Fig. 2, into engagement with the thread loop *l* which, at this time, is held by one of the loopers 21 and extends from the work about said looper to the needle 20, as shown in Fig. 6. The element 75 is formed with a blunt or rounded forward edge *e* which is intersected by an inclined cutting edge *f*. As said element 75 is moved across the throat plate from the normal position shown in Fig. 2 through the position shown in Fig. 6 into the position shown in Fig. 7, the blunt edge *e* thereof first engages the leg *l'* of the loop *l* leading from the needle, deflecting the same, and thereby drawing the other leg *l''* leading from the work about the looper 21, tensioning said leg *l''* and acting to set the last stitch. Thereafter, as the element 75 moves into the position shown in Fig. 7, the cutting edge *f* engages the tensioned leg *l''* and severs the latter.

The trimming element or thread engaging member 75 is provided with an opening to receive a stud 76 carried by an arm 77 fast on one end of a rock shaft 78 journaled in suitable bearings in the bed 15 and having secured to its opposite end an arm 79. Pivotedly connected to the arm 79 is a link 80 guided on the outer side of the bed on a screw 81 projecting from said bed and received in a slot 82 in said link. At its end opposite its connection with the arm 79 the link 80 is formed with a notch 83 adapted to be entered by a nose 84 on a collar 85 secured to the stop bolt 41.

When the nose 43 of the stop bolt 41 enters the notch *c* in the cam 44 under the influence of the spring-pressed plunger 45, as above explained, and as shown in Fig. 4, the nose 84 enters the notch 83. Thereafter, when the stop bolt 41 yields under the impact of the shoulder *d* on the nose 43, the link 80 is moved toward the left in Fig. 4, thereby turning the shaft 78 and operating the trimming element 75 as above described. Should the button hole cutter 50 be jammed in the work, or otherwise fail to rise promptly under the influence of the spring-pressed plunger 45, its connection with the stop arm 34 will prevent the nose 43 from entering the notch *c* and hold said stop arm in the position shown in Fig. 5. The nose 84 is thereby prevented from entering the notch 83, so that the subsequent yielding of the stop bolt 41 under the impact on the nose 43 of the stop shoulder *d* (which stop shoulder is of sufficient length to engage said nose 43 even when the stop arm 34 is in the position shown in Fig. 5) will not produce any movement of the link 80, the trimmer element 75 will not be actuated, and all danger of interference thereof with the jammed button hole cutter is prevented.

I claim:

1. In a buttonhole sewing machine, a driving shaft, stop mechanism therefor including a stop

arm movable in one direction into and out of stopping position, said shaft having a stop shoulder and said stop arm having a yielding stop element engageable thereby when in stopping position, means operable when said stop arm is in stopping position, and prior to the engagement of said stop shoulder with said stop element for moving said stop arm in another direction, a buttonhole cutter connected with said stop arm and actuated by the movement thereof in said last named direction, a thread cutter, and means actuated by the yielding movement of said stop element for operating said thread cutter, said last named means including a connection rendered operative or inoperative by the buttonhole cutter actuating movement of said stop arm.

2. In a buttonhole sewing machine, a driving shaft, means for controlling the application of

power to and for stopping said shaft including a stop arm having a yielding stop bolt, a cam on said shaft having a stop shoulder, said stop arm being movable out of and into the path of movement of said cam and simultaneously to apply or discontinue the application of power to said shaft, a buttonhole cutter connected with said stop arm and moved therethrough by said cam into projected or cutting position, spring means 5 for retracting said cutter and arm when permitted by said cam, a thread cutter, and means for operating said thread cutter by the yielding movement of said stop bolt when engaged by said stop shoulder, said last named means including an element operatively engageable with a portion of said stop bolt when said stop arm is in a position corresponding to a retracted position of said buttonhole cutter.

JOSEPH H. PIKUL.
